FURNACE DUST TRAP

Sam D. Rich, Madeira, Ohio

Application August 10, 1944, Serial No. 548,831

3 Claims. (Cl. 126—242)

1

The present invention relates to furnaces, particularly of the household type, and has for an object the provision of a simple and inexpensive dust trap whereby the escape of dust and smoke into the furnace room is eliminated during the operations of tending the furnace and removing the ashes.

Another object of the invention is to provide a device of this kind which controls furnace room air currents in the vicinity of the firing front of the furnace and which assists in preventing back drafts in the flue from releasing smoke through the fire door openings into the free atmosphere of the furnace room.

Still another object of the invention is to provide a light-weight device of this kind which can be folded into a thin flat parcel that is inexpensively packed for individual shipment through the mails and otherwise and which may be packed and stored in quantity in a minimum of space.

A further object of the invention is to provide a device of this kind which is readily applied to and removed from operative relation with a furnace.

These and other important objects are attained by the means described herein and exemplified in the accompanying drawings in which:

Fig. 1 is a fragmental front elevational view of a household furnace having a device of the invention operatively associated therewith.

Fig. 2 is a view taken on line 2—2 of Fig. 1.

Fig. 3 is a perspective view showing a device of the invention in folded and collapsed condition.

Fig. 4 is a fragmental side elevational view of a household furnace with a device of the invention permanently secured thereto and disposed in an inoperative position.

Heretofore the operation of household solid fuel burning furnaces has been universally attended by the escape of ash dust into the furnace room in varying degrees during the operation of shaking the furnace grates and during the removal of the ashes from the ash pit. The heavier portions of the escaping ash may settle throughout the furnace room, while the lighter particles are air borne from time to time to various parts of the household and they constitute not only a source of so-called household dirt and damage to house furnishings but in addition to this they are more recently recognized as inimical to the health of occupants.

Insofar as is known, the previous attempts to combat these evils have resulted in relatively complicated and expensive devices, many of

which were not entirely satisfactory for various reasons.

By the present invention there is provided a very simple and easily accommodated structure which sets up a beneficial control of the furnace room air currents in the immediate vicinity of the firing front thereof so that when the fire door and, or, ash pit door, as well as the control louvers or draft openings of either, are open these furnace room air currents are constrained to follow a general course into the furnace itself and to carry with them floating dust particles, traces of smoke and fumes, due to the back drafts in the furnace, which would otherwise eventually travel about in the free atmosphere in the room. By this same means that portion of extraneous household dust which may come into the effective area controlled by the device is likewise trapped and removed.

20 In its preferred form the device of the invention is arranged and constructed so that it is of practically universal application to the wide variety of household solid fuel burning furnaces that are now in use. In this form also the device is very light in weight and is arranged to be collapsed or knocked down into a thin flat form as shown in Fig. 3.

In the preferred construction the dust trap indicated generally at 10 comprises a top wall member 11 of flat light gage metal having a length somewhat in excess of the width of a furnace ash pit door, while the width of said top wall is desirably greater than the width of the firing door so that the top wall will project somewhat beyond the edge of the firing door when the latter is open at approximately right angles to the front of the furnace. Movably or removably connected, for example by an integral hinge portion 12, is a side wall member 13 which may be somewhat narrower than the top wall but which has the rear edge 14 normally disposed in a common plane with the corresponding rear edge 15 of the top wall 11. The side wall 13 is intended to provide an imperforate baffle from the floor to the elevation of the top of the firing opening 150 of a furnace. In order to accommodate the side wall to varying heights of furnace firing doors, an extension or slide 16 is applied for longitudinal adjustment over the bottom of wall 13. This may be provided in any suitable fashion, for example, by providing opposed edge channels 17 on the longitudinal edges of the extension 16 so that the side wall 13 may be slidably adjusted therein. A slot 18 in extension 16 has a bolt and nut structure, indicated at 19, inserted therein and

through a perforation in the wall 13. I prefer to provide the under side of the projecting portion of the top wall 11 with a plurality of longitudinally disposed parallel creases 19 which are impressed very lightly into the sheet metal to facilitate the manipulation of the front edge of the top wall by hand to form a slightly down-turned front flange 20 when desired. The extreme forward edge 21 of the top wall may be finished smooth by forming a bead thereon.

It should be noted that in its preferred form the rear edges 15 and 14 of the top and side walls respectively are left with raw edges so that should the contour of the front casting of the furnace require it, the edges of said members may be notched to accommodate projections on the furnace. Due to the thickness of the metal such notchings may be effected by means of an ordinary scissors or a tin snips.

It will be understood that the structure of the hinge 12 may be of any convenient form, such as by integral tubular complementary hinge portions arranged in staggered relation on the respective members and connected by means of a pintle 22 formed of a suitable length of ordinary stiff wire.

Applying the dust catcher 10 to a household furnace such as 23, the extensible slide wall 13-16 is positioned at approximately 90° to the top wall 11 and the said top wall is positioned immediately above the top of the fire door opening 150. The slide or extensible member 16 is then adjusted relative to the side wall 13 so as to span the distance from the top wall to the floor 24 of the furnace room and, upon tightening the nut and bolt structure 18 or a comparable securing means, the side wall serves as a vertical leg to support the top wall at its one end. In those furnaces on which there may be found a horizontal rib or flange closely above the top of the fire door opening 150, the device, when extended to an inverted L-shape, may be disposed against the furnace with a rear edge of the top wall resting on such a rib or ledge. With the raw rear edges of the top wall and side wall in substantial abutment against the furnace front, the dust trap of the invention is thus fully supported for use without any further fastening means. Should the furnace to which the device is to be applied, be without a suitable horizontal front ledge above the fire door opening 150, as is commonly found and as illustrated in the accompanying Figs. 1 and 2, the top wall 11 is placed upon the top edge of the fire door 25 when the latter is open and at approximate right angles to the front of the furnace and this is the operative position in which the fire door should remain when the furnace grates are shaken and when ashes are being removed through the ash pit door opening 26.

The furnace illustrated in Figs. 1 and 2 has the commonly found arrangement wherein the firing door opening 150 is located immediately above the ash pit door opening 26, and the respective doors 25 and 27, which control said openings, have their respective latches 250 and 270 on a common vertical side of said doors. The latch keepers 251 and 271 are accordingly located on the furnace front adjacent the so-called latch side of the respective door openings.

In operation, with the firing door 25 and ash pit door 27 in open position as shown, and the device supported in operative position with side wall 13-16 extending adjacent the latch side of the door openings 26-150 (see Fig. 1), the smoke pipe 28 would have the flue damper 29 in open position in the manner well known to most persons as

proper whenever the fire door is open for any reason whatsoever. At that time the optimum draft is established through the fire door opening, the smoke pipe and the stack or chimney. The effective zone of suction or air intake through the fire opening is extended forwardly of the furnace by the positioning of the dust trap of the invention as illustrated. Air currents in the furnace room at this time are constrained to pass between the side wall 13-16 and the open firing door and ash pit door 25 and 27. The draft or suction into the firing door 150 is thus increased so that in this zone it is possible to freely shovel ashes from the ash pit 26 and deposit them in a bucket or other receptacle seated on the floor within said zone without the usual puffing and scattering of ash dust into the free atmosphere of the furnace room. Instead the liberated fly ash and dust is entrained in the air currents flowing from various directions to the front of the resulting trap or draft structure and from the lateral space between the bottom of firing door 25 and ash pit door 27. Floating dust particles of extraneous origin likewise become entrained under the altered condition of air currents in the furnace room and their movement into the fire door opening 150 can be readily observed with the aid of concentrated beams of light operating in a condition of subdued general lighting or of substantial darkness.

It will be understood that whereas the readily removable dust trap thereinbefore described is of the preferred form for the purpose of independent merchandising, a substantially similar structure may be permanently appended to a furnace in any suitable manner by hinging the rear edge 15 of the top wall 11 to the front of the furnace casting above the fire door so that the device may be folded compactly against the furnace by first folding the side wall about its hinged connection to lie on top of the top wall and then tilting the top wall upwardly about its rear hinged mounting, as shown in Fig. 4. In Fig. 4 the side wall 130 is shown disposed between the furnace and the upturned top wall 111, the top wall being hinged as at 30 on a horizontal rib or bracket 31 suitably affixed to the front of the furnace 23. When it is desired to utilize the dust trap and the back draft baffling effects of the device it will be unfolded to assume a position as shown in Figs. 1 and 2.

Under conditions of low barometer and wind, it will be found desirable to leave the device of the invention operatively associated with the front of the furnace so that when momentary back drafts in the chimney cause slight puffs of smoke to escape from the fire door draft control 32 (see Fig. 2) the resumption of normal draft will again draw the escaped smoke and fumes back into the furnace through the opening from whence they originally escaped, due to the control zone which is set up between the top wall member and the adjoining side wall member.

What is claimed is:

1. The combination with a household furnace having a door controlled firing opening and an ash pit opening, of a dust trap device comprising a top wall member adapted for edgewise abutment horizontally on the front of the furnace above the fire door opening, and a side wall member extending downwardly from one end of said top wall to the floor and serving as a support for said end, the other end of said top wall being adapted to be supported by the fire door in its open position.

2. A dust trap forming device for a household furnace consisting of a top wall and a side wall extending downwardly from one end of said top wall, said walls adapted for edgewise abutment with the front of a furnace having an ash pit door and a firing door with their latches on a common side for partially enclosing the door area in front of the furnace and bounding said area continuously along the latch side of the ash pit and firing door openings of the furnace and along the top edge of the firing door opening, the free end of the top wall adapted to rest on the top of the fire door of the furnace in its open position.

3. A furnace dust trap forming device comprising a top wall and a side wall member hingedly connected to form an inverted L-shaped housing for deposition against the front of a furnace which has a fire door controlling a firing opening therein and an ash pit door controlling an ash pit opening therein, said top wall adapted for support at its free end by said fire door in its open position, said side wall member adapted to rest endwise on the floor and to extend upwardly alongside said openings in the furnace.
